UNITED STATES PATENT OFFICE.

WILLIAM S. ROBINSON AND CHARLES A. HAESELEY, OF FANCY FARM,
KENTUCKY.

AUTOMATIC LOCKING AND RELEASING MECHANISM FOR TRANSOMS OR WINDOWS.

SPECIFICATION forming part of Letters Patent No. 595,922, dated December 21, 1897.

Application filed August 31, 1897. Serial No. 650,185. (No model.)

To all whom it may concern:

Be it known that we, WILLIAM S. ROBINSON and CHARLES A. HAESELEY, citizens of the United States, residing at Fancy Farm, in the county of Graves and State of Kentucky, have invented new and useful Improvements in Automatic Locking and Releasing Mechanism for Transoms or Pivotaly-Supported Window-Sashes, of which the following is a specification.

This invention relates to an automatic locking and releasing mechanism for transoms and pivotally-supported window-sashes that are arranged to swing in a frame.

15 It is the object of our invention to provide a ratchet journal mechanism through which a transom or pivotally-supported sash can be held at any adjusted position and to provide for operating, locking, and releasing the sash 20 in a simple manner.

25 The invention consists in features of construction and novel combination of parts in a locking and releasing mechanism for transoms or window-sashes, as hereinafter described and claimed.

30 In the annexed drawings, illustrating the invention, Figure 1 is a front elevation of a window or transom partly lowered or opened and broken away to show the location of the locking journal mechanism. Fig. 2 is an elevation of the journal locking and releasing mechanism from the rear or inner side. Fig. 3 is a sectional view taken on the line 2 2 of Fig. 2 and viewed in the direction of the arrows, showing the parts in a horizontal position or in the position they would occupy when the window or transom is adapted to swing laterally. Fig. 4 is a perspective view of the ratchet-gear. Fig. 5 is a like view of 35 the pawl; and Fig. 6 is a sectional view through this sash and its frame, showing the shiftable pivot.

40 Reference being had to the drawings, the numeral 1 designates the frame of a window or transom, and 2 the sash. In an inner face of the frame, at one side, is a mortise to receive a metal plate 3 and a recessed portion to accommodate the working mechanisms of our device, which are confined between the 45 plate 3 and a face-plate 4. The plate 3 may be secured in place by screws or otherwise

and has a circular opening 5, which, with a similar opening 6 in the face-plate 4, affords a bearing for the journal 7 of the ratchet-gear 8. The ratchet-gear and journal may be 55 cast integral, or the ratchet-gear may be made fast to the journal in any suitable manner. Between the plates 3 and 4 there is arranged a pawl 9 to engage and interlock with the teeth of the ratchet-gear. This pawl 9 is 60 loosely mounted on a pivot-pin 10, which is secured and supported in suitable openings provided in the plates 3 and 4. It will be observed that the pawl is so arranged as to drop automatically into engagement with a tooth 65 of the ratchet-gear 8 at one point or another, according to the degree to which the sash 2 is opened, thus securely holding the sash in its adjusted position. The journal 7 has at its outer portion a squared end 11, which fits into 70 a correspondingly-squared opening 11^a of a socket-plate 12, that is countersunk in and secured to one edge of the sash, and thus as the sash is swung toward an opened or closed position the journal 7 and attached ratchet-gear 8 will receive a corresponding movement, 75 and the degree at which the sash is opened or left open will be regulated by the engagement between the ratchet-gear and pawl 9, which will hold the sash in any required position. 80

For the purpose of releasing the pawl 9 from the ratchet-gear 8, so that the sash will be allowed to assume a closed position, we provide the following construction: The ratchet-gear 8 has a flanged portion 12^a, which is provided with a recessed portion 13. Below this recess the rim of the flange is cut away slightly to leave a projecting portion 14, and below this part the flange is removed for a considerable space, affording the opening 15. On its 85 periphery the ratchet-gear is provided with a guide-groove 16, which is curved slightly outward at 17, above the recess 13, as shown, and extends downward to a point below the recess 13, or it may be continued to the opening 15. The outer edge of the groove 16 is beveled or slanting, as shown at 18, for a purpose to be presently explained. The pawl 9 has a depending tapering tongue 19, which has at its lower end an outwardly and downwardly extending guide-finger 20, which is adapted to work in the guide-groove 16. The 90 95 100

distance between the projecting portion 14 and the inner side of the plate 3 is sufficient to allow a space for the tongue 19 to pass through as the gear is revolved. The upper 5 edge of the recess 13 forms a shoulder 21, which in operation is adapted to trip the tongue 19 to raise the pawl 9.

The opposite side or edge of the window or transom is supported or journaled in the 10 manner described and illustrated in our application, Serial No. 643,999, filed July 9, 1897. This is accomplished by means of a longitudinally-shiftable pivot-pin 26 in a plate 27, that is countersunk in the edge of the sash, 15 which is also mortised to receive the said pivot-pin when pushed inward. The inner end of the pivot-pin 26 is provided with a head 28, that limits its outward movement. A suitable recess intersects the pin-receiving 20 mortise, and when the pivot-pin 26 is pushed outward, as by a suitable tool or instrument inserted through said recess or opening in the side of the sash, a plug 29 may then be pressed into said recess, at the rear of the 25 pivot-pin 26, to hold it in its projected position. The projecting end of the pivot-pin 26 is received in a socket-plate 30, that is mortised or countersunk into an inner face of the frame 1, and thus by means of the journal 7 and pivot-pin 26 the sash 2 is supported or journaled in its frame.

The operation of the device is as follows: The transom or window is turned by pulling a suitable cord or otherwise to open it, thereby 35 through the engagement of the squared end 11 with the squared opening 11^a of the socket-plate 12, secured in the sash of such transom or window, turning the journal 7, and with it the ratchet-gear 8, the pawl 9 sliding over the 40 teeth of the ratchet in the well-known manner until the transom or window has been opened to the desired extent, when the pawl 9 engages with one of the teeth on the ratchet-gear 8 and locks the sash in that position. 45 Should it be now desired to close the transom, it is further turned in the opening direction, when the shoulder or stop 21 will engage the tongue 19 and operate to raise it through the recessed portion 13 until the guide-finger 20 50 passes over the stop 21 and slides down the slanting side 18 and drops into the groove 16. At this point a stop 22, which may be one of the teeth of the ratchet-gear, engages with a brace-piece 23, which is secured between 55 the plates 3 and 4 and prevents the further turning of the gear, which might disarrange the working connection of the parts. The transom is now permitted to close, when the ratchet-gear is turned in the reverse direction, 60 and the guide-finger 20 slides in the guide-groove 16, thereby maintaining the pawl in an elevated position to prevent it coming in contact with the teeth of the ratchet-gear. The arrangement of the parts is such that as 65 the transom or window reaches the closed position the finger 20 arrives at the opening 15, and the tongue 19, falling therein, per-

mits the pawl to resume its operative relation with the ratchet-gear.

A spring-latch 24 may be secured to the 70 sash and provided with a depending cord 25, which serves at the same time as a means for withdrawing the said latch and to shift the sash to any required position, whether wholly or partly open.

It has been assumed that the locking journal mechanism at one side of the sash and the longitudinally-shiftable pivot-pin at the other side will be each arranged at such an elevation that the weight of the sash will be ordinarily sufficient to move it toward or to a closing position, when the engagement of the ratchet-gear and pawl is released by a suitable pull on the cord. Should the weight of the sash not be sufficient, a spring may be 85 provided for the purpose of closing it.

In Fig. 3 we have shown the device turned to the position it would occupy when applied to a transom or window adapted to swing laterally. In this construction we would use a 90 spring 31, suitably located in the device for returning the window to a closed position, and a spring 32, bearing on the pawl 9, to insure positive contact between it and the ratchet-gear 8. Either or both of these springs 95 might be used with advantage in the construction of window first described.

By means of the longitudinally-shiftable pivot-pin 26 the sash is very readily engaged in or disengaged from its frame without disturbing the ratchet journal locking mechanism, it being only necessary to withdraw the plug 29 in order to gain access to the pivot-pin 26, so as to move it longitudinally inward or outward.

A transom or window-sash journaled on this automatic locking and releasing mechanism cannot be lifted out of the frame by windstorms or by careless handling, for in its closed position and in its open position the 110 sash is securely fastened into the frame.

Having thus fully described our invention, what we claim is—

1. In a ratchet-and-pawl locking and releasing mechanism, the combination with a 115 ratchet-gear having a guide-groove of a pawl coacting with said ratchet-gear having a tongue adapted to engage with the guide-groove, and means operating by the forward turning of the ratchet-gear to raise said 120 tongue, and with it the pawl, to bring the tongue into engagement with the guide-groove, whereby, in the reverse movement of the ratchet-gear, the pawl is maintained in an elevated position and out of contact with 125 the teeth of the ratchet-gear, substantially as described.

2. In a ratchet-and-pawl locking and releasing mechanism, the combination with a 130 ratchet-gear having a guide-groove, of a pawl coacting with said ratchet-gear having a tongue adapted to engage with the guide-groove, a stop operating by the forward turning of the ratchet-gear to raise said tongue, and

with it the pawl, to bring the tongue into engagement with the guide-groove, whereby in the reverse movement of the ratchet-gear the pawl is maintained in an elevated position and 5 out of contact with the teeth of the ratchet-gear, and means to return the tongue to normal position and permit automatic reengagement of the pawl and ratchet-gear, substantially as described.

3. In a ratchet-and-pawl locking and releasing mechanism, the combination with a ratchet-gear, of a flange thereon having a guide-groove, a pawl coacting with the ratchet-gear and having an integral depend-

15 ing tongue adapted to engage with the guide-groove, and a stop on said ratchet-gear operating in the forward turning thereof to raise said tongue, to bring it into engagement with the guide-groove, whereby, in the reverse 20 movement of the ratchet-gear, the pawl is maintained in an elevated position and out of contact with the teeth of the ratchet-gear, substantially as described.

4. In a ratchet-and-pawl locking and releasing mechanism, the combination with a ratchet-gear of a flange thereon having a guide, a pawl coacting with the ratchet-gear and having an integral depending tongue carrying a guide-finger adapted to engage with

30 the guide-groove, a stop on said ratchet-gear operating in the forward turning thereof to raise said tongue to bring its guide-finger into engagement with the guide-groove, and means for limiting the forward turning of the ratchet- 35 gear, substantially as described.

5. In a ratchet-and-pawl locking and releasing mechanism, the combination with a

ratchet-gear, of a flange thereon having a guide-groove, a pawl coacting with the ratchet-gear and having an integral depend- 40 ing tongue carrying a guide-finger adapted to engage with the guide-groove, recesses formed in said flanges to permit the tongue to be raised and lowered, a stop on said ratchet-gear operating in the forward turning thereof 45 to raise said tongue to bring its guide-finger into engagement with the guide-groove, and means for limiting the forward turning of the ratchet-gear, the combination being and operating substantially as and in the manner 50 herein set forth.

6. The combination with the frame and sash of a transom or swinging window, of a locking and releasing mechanism located in said frame and comprising a journal engaged with 55 the sash and turning therewith, a ratchet-gear carried on said journal having a guide-groove, a pawl coacting with the ratchet-gear and having an integral depending tongue adapted to engage with the guide-groove, 60 means on said ratchet-gear operating in the forward turning thereof to raise the tongue into engagement with the guide-groove, and a spring operating on said journal and tending normally to maintain the window or transom closed, substantially as described.

In testimony whereof we have hereunto set our hands in presence of two subscribing witnesses.
